(57) **CLAIM**

I claim the ornamental design for a throwing game board apparatus, as shown and described.

DESCRIPTION

FIG. 1 is a front isometric view of a throwing game board apparatus showing my new design;

FIG. 2 is a rear isometric view thereof;

FIG. 3 is a front elevation view thereof;

FIG. 4 is a right side elevation view thereof;

FIG. 5 is a top plan view thereof;

FIG. 6 is a bottom plan elevation view thereof; and,

FIG. 7 is a front isometric disassembled view thereof.

The broken lines shown in FIG. 7 depict portions of the throwing game board apparatus that form no part of the claimed design.
